SELF-HEATING SADIRON

Chester A. Hoff, Akron, Ohio, assignor to The Akron Lamp Company, Akron, Ohio, a corporation of Ohio

Application February 28, 1934, Serial No. 713,255

7 Claims. (Cl. 158—23.2)

This invention relates to improvements in self-heating sadicons, particularly of the type which is heated by the combustion of gasoline or other combustible fluid, although certain features of the invention may be extended to the construction of irons heated by electricity.

One of the objects of the invention is to provide an iron of the type heated by gasoline or the like so that the iron may be placed on end or in raised position when not in use. Heretofore irons heated by gasoline were provided with a reservoir carried on the rear of the iron which prevented it from being turned up when out of use temporarily. The usual electric irons are provided with an attached bracket which serves as a stand upon which the iron rests, and it is one of the features of the invention to construct an iron of the gasoline heating type which can be set up in similar fashion during a pause in the ironing. This purpose makes it essential that the construction and organization of the iron be completely changed and modified.

Another purpose of the invention is to provide a new and improved construction by which the needle may be removed quickly and easily for the purpose of cleaning.

Further objects are an improved organization whereby the handle is insulated from the body of the iron, and the construction and mode of attachment of the base to the body whereby it can be easily removed and reattached so that the inner or working parts of the iron are readily accessible for inspection and cleaning, and further so as to enable this element to be plated and finished separately from the body.

These and other objects and advantages will become evident from the detailed description and drawings which show the best known or preferred form of the invention, it being understood that changes and modifications may be made therein, within the scope of the invention as set forth in the claims.

In the drawings,

Figure 1 is a side elevation of the improved iron, the handle being shown in vertical cross-section;

Figure 2 is a plan view of the iron;

Figure 3 is a vertical transverse section on the line 3—3 of Figure 1, looking toward the rear of the iron;

Figure 4 is a similar section on the line 4—4 of Figure 1, looking toward the front of the iron;

Figure 5 is an enlarged detail section of the 55 feeder and vaporizing tube;

Figure 6 is a detailed section of the handle attachment on the line 6—6 of Figure 1;

Figures 7 and 8 are detailed views of the attachment of the handle and reservoir;

Figure 9 is a detailed section of the mixing 5 chamber;

Figure 10 is a detail of valve-control handle on the line 10—10 of Figure 5.

Figure 11 is a detail sectional view of the reservoir shown without supporting bosses.

The iron comprises a main casting or body 1 which is of the usual shape of a sadiron and is hollow to accommodate the burner. On the inner forward end of the body is a pin 2 and on the rear of the body is a fastening screw or pin 3. 15 The base of the iron is indicated at 4 and is provided with an upstanding flange 5, which, with the hollowed out central portion 6 of the base constitutes a chamber in which combustion occurs. The flange serves as a shield about the 20 flame from the air entering the chamber through openings 8 in the lower edge of the body. The front of the flange is formed with a slot or recess to receive the pin 2. The rear of the flange is provided with a threaded hole to receive the 25 screw 3. By withdrawing the screw the base can be removed from the body, there being enough play between the body and the base to free the pin 2. By constructing the base so that it is easily removed and replaced the interior of 30 the iron may readily be inspected and cleaned. Furthermore it is possible to electroplate and finish the base as a separate element, thereby improving and cheapening the manufacture of the 35 iron.

The handle is indicated, as a whole, by the numeral 15 and consists of a wooden grip element 16 which is hollow throughout to accommodate a filling tube 17 accessible at the forward end and closed by a cap 18, the interior of which 40 is screw threaded to fit over the enlarged screw threaded end of a removable plug 20, the inner end of which is reduced and screwed into the tube. A nut 21 surrounds the plug and serves to hold in position a block of heat insulating material 22 which is set in a recess in the forward end of the handle. Mounted in the plug and held in position by the cap 18 is a valve member 24 containing a usual ball valve or the like, the outer end of the valve being provided with a flange 50 contacting a seating gasket 25. In the outer end of the valve member is a plug or stopper 26 having an angled passage through which air, under pressure, may be introduced into the reservoir. The inner end of the plug is ground to make a 55

seating fit with a corresponding seat in the valve member. When the air within the reservoir is under operative pressure, the plug is screwed home, but when the pressure is to be increased 5 the plug is relaxed and is connected to the delivery end of a pump or the like.

At the rear of the grip 16, the tube 17 is extended and screw threaded to receive the upper end of the fuel reservoir 39. This reservoir is 10 preferably substantially triangular and flat on its rear face, although its shape may be varied, and extends downwardly at the rear of the iron to a point near the body. The usual reservoir on irons of this type is a ball carried upon a bracket 15 at the rear of the iron and filled from the top. Not only is this awkward but it makes it impossible to stand the iron in a substantially vertical position upon its end when temporarily out of use. With these irons it has hitherto been necessary to provide a stand upon which the iron is 20 placed during a pause in the ironing. The natural movement of the ironer is to stand the iron on end, and so far as known to me the present construction is the first by which it is possible to 25 do this with an iron heated by liquid fuel.

The rear face of the reservoir, as shown, inclines outwardly and downwardly and is provided at its lower rear edge with a flange 31 which is at right angles to the axis of the iron. Near the 30 top of the reservoir are two studs 32 which with the flange form a rest upon which the iron may be placed while temporarily out of use. It is obvious that this particular arrangement and design is not essential and that the side of the reservoir may be flat, as shown in Figure 11, or other means provided whereby the iron may be rested in tilted or upright position. The position of the reservoir assures the substantially upright position of the iron. Housewives are apt to forget 40 to place the iron on a stand and thus scorch the clothes or ironing board. By redesigning the iron and altering the usual and accepted construction of irons of this type so that it may be stood in the manner described the sadiron of the 45 burner type is greatly improved.

The handle and reservoir are secured to the base by a single curved strap 35, the forward end of which is bent upwardly and received in the insulation plate 22. The central portion of 50 the strap is received on two posts 36 rising from the body 1 and held in position by a long screw 37 at the front and a short screw 38 at the rear. The long screw serves as a means for holding the burner and mixing chamber in position. The 55 rear end of the strap is offset and notched as at 40 with a keyhole shaped slot to be received over a screw threaded post 41 on the underside of the reservoir, a nut 42 being received over the post and having a circular extension received in the 60 enlarged bore of the slot 40. By the construction described, the handle and reservoir are adequately insulated from the hot body of the iron, and the reservoir serves as a connector between the handle and body of the iron.

65 At one side of the lower end of the reservoir or fount 30 is located the discharge opening 45 which is preferably formed as a depressed boss in which is received the upstanding feed pipe 46 formed as a branch of the T-shaped coupling 48. 70 A threaded sleeve 49 and gasket 50 resting against a flange 51 on the pipe 46 hold the coupling in place.

An elbow 59 which extends at its open end to the base of the fount conducts the fuel to the 75 outlet. This assures the feed to the burner when

the iron is in upright position as it takes fuel from the deepest point in the fount when the iron is standing in idle position.

The coupling is formed with a through passage restricted at 52 to provide a valve seat. At the rear of this seat is a screw-threaded valve 54, the fuel passing around the threads and through the valve, which is adjusted so as to regulate the flame. The valve is extended rearwardly and provided at its rear end with a collar 55 to which is secured the knurled handle 56. A plug 57 and packing glands 58 surround the valve and make a fluid tight seal at this point.

To the forward end of the coupling 48 is screwed a thimble 60 in which is soldered the 15 vaporizer tube 61 which extends to a point near the front of the iron where it discharges into a mixer to be described later. The discharge end of the vaporizer tube is closed by a diaphragm 62 in which is located the capillary opening 20 through which the fuel is discharged. The needle 65 extends through the vaporizer tube and through the coupling to the rear where it passes beyond the valve 54 and is enlarged slightly. It is held in position by a cap 66. The forward end 25 of the needle is reduced to enter the capillary opening in the diaphragm and is preferably provided with a slight taper. When the handle 56 is rotated the valve and needle move in unison in or out to regulate the flame at both the valve 30 seat 52 and diaphragm 62. A coil 67 surrounds the needle in the vaporizer tube and serves to break up the flow of fuel so that it vaporizes more efficiently in the tube. The needle may be removed from the tube by the removal of the cap 35 66. This gives easy accessibility to the needle and permits its ready removal without disconnecting the iron. It is a very considerable advantage in irons of this type to have easy removability of the needle in the event that the 40 passage becomes clogged.

The mixer for forming the combustible mixture of air and gasoline vapor and the burner are formed as a single casting and held in position principally by the long screw 37 which is tapped 45 into the mixer casting 70. The interior of the casting is formed as a chamber 71 into which the fuel pipe 61 discharges. An air pipe 72 also discharges into the chamber. This pipe extends rearwardly to a point at the rear of the 50 iron where it is secured in the outside of the body 1. From the mixing chamber the burner extends rearwardly over the base of the iron. This burner 73 may be of any ordinary or usual construction, being shown as slotted to provide 55 the burner openings 74 which direct the flame against the upper side of the base. From one side of the burner extends a nozzle 75, the end of which is perforated so that a flame plays against the fuel pipe 61 and thus serves to vaporize the fuel. Over the top of the burner and on top of the mixer is located a shield 76. A hole 78 in the side of the body is used for lighting the burner.

Although the construction is described in detail, it will be understood that the invention is not limited or confined to such detail construction, but may be varied within the scope of the invention as set forth in the appended claims. While some of the features are peculiar to a 70 fluid pressure burner, others such as the insulation of the handle and the removable base may be incorporated in an electrically heated iron.

What is claimed is:

1. A self-heating iron of the fluid burner type 75

having a body, a handle, a reservoir forming a connection between the body and the handle, and means for supporting the iron located solely upon the reservoir.

- 5 2. A self-heating iron of the fluid burner type comprising a body, a burner within the body, a handle, a reservoir at the rear of the iron and forming a connection between the body and the handle, iron rests formed upon the reservoir, a
10 feed pipe leading from said reservoir to said burner, and an elbow disposed within said reservoir to supply fuel to said feed pipe from approximately the lowest point in the reservoir both in normal position and also when upon the rests.
15 3. A self-heating sadiron comprising a body, a fluid burner located within the body, a handle, an enlarged reservoir for holding liquid fuel under pressure located at the rear of the iron and connecting the handle and the body, iron rests
20 upon the reservoir adapted to support the iron when the body is elevated, and a fuel supply pipe leading to the burner from substantially the lowermost point of the reservoir in either operating or elevated position of the iron body.
25 4. A self-heating sadiron comprising a body, a fluid burner located within the body, a handle, an enlarged reservoir for holding liquid fuel under pressure located at the rear of the iron and connecting the handle and the body, the
30 rear face of the reservoir being inclined downwardly and rearwardly, iron rests upon the rear

face of the reservoir adapted to support the iron when the body is elevated, and a fuel supply pipe leading to the burner from substantially the lowermost point of the reservoir in either operating or elevated position of the iron body. 5

5. In a sadiron, a body, a liquid fuel burner in the body, a handle, and an enlarged reservoir located at the rear of the iron and extending between the handle and the body and extending rearwardly of the body, the rear face of the 10 reservoir being substantially flat and adapted to form an iron rest when the body is elevated.

6. In a sadiron, a body, a liquid fuel burner in the body, an enlarged reservoir located at the rear of the body adapted to hold fuel under pressure, the rear face of the reservoir serving as a support for the iron when the body is elevated, and a feed pipe leading from substantially the lowermost point in the reservoir in either position of the iron and delivering to the burner. 15

7. In a sadiron, a body, a liquid fuel burner in the body, an enlarged unitary reservoir located at the rear of the body, a handle connected to the upper end of the reservoir, a reservoir feed pipe 20 extending longitudinally through the handle, a strap, the ends of which are connected to the base of the reservoir and the end of the handle, and means located intermediately of the strap to support the iron body. 25
